UNITED STATES PATENT OFFICE.

RICHARD M. BEARD, OF NEW YORK, N. Y.

INTERCOMMUNICATING TRUNK-LINE TELEPHONE SYSTEM.

1,135,654.

Specification of Letters Patent. Patented Apr. 13, 1915.

Application filed March 1, 1907, Serial No. 360,006. Renewed August 25, 1914. Serial No. 858,520.

To all whom it may concern:

Be it known that I, RICHARD M. BEARD, a citizen of the United States, residing at New York city, in the county of New York and State of New York, have invented certain new and useful Improvements in Intercommunicating Trunk-Line Telephone Systems, of which the following is a full, clear, and exact description.

10 My present invention relates generally to telephone systems, and specifically to an intercommunication trunk system for connecting two or more groups of intercommunication telephones, each of which said 15 groups is wired according to a modification of a method fully set forth in my former patent application Serial No. 292,916, filed December 22, 1905.

The system of my former application is, 20 like all other intercommunication systems in one respect, subject to a certain limitation, inasmuch as it is not readily adaptable to a very great number of stations. The necessarily large number of wires required 25 constitutes a practical limitation of the number of stations, and besides the station to station method does not readily lend itself to the needs of a large factory, or other institution, having a great number of telephones. Such 30 institutions are usually systematically divided into a number of departments, each of which is under a responsible head, and each department is as a rule so extensive as to require several telephones. It is found 35 objectionable from the standpoint of proper system and discipline, for the party at any telephone to be able to call and talk directly with any other station in the system. Although it is important to have telephones 40 located at many places to reach the lesser employees, it is also a prerequisite of good management for the responsible heads to exercise a certain amount of supervision.

The small isolated central exchange has 45 the objection that another separate telephone, or system of telephones, has to be used for talking with the outside public; and the private branch exchange for handling both local and outside traffic has the 50 disadvantage that any station in the local system can get connection through the switchboard with the outside world. Manufacturers of the latter type of switchboards have frequently been called upon to

build a switchboard in which it is impossible for certain local stations to be connected with the public system. This has the serious objection of inflexibility. Without some inflexible construction of the switchboard, the local operator must be relied upon to use individual judgment in making proper connections. In this matter, it is as difficult for a central operator to exercise authoritative control over the traffic, as it for any central official to direct the details of so large an establishment. Departmental division under many responsible heads is the accomplished fact in the management of great institutions, such as large manufacturing plants, government or municipal buildings, hospitals or other eleemosynary and public or semi-public institutions, but a suitable telephone system is still wanting.

The intercommunication method is peculiarly adapted to the requirements of establishments where it is important to have the telephones located at various points for quick exigencies, but where the pressure of traffic is low. This is the exact condition which prevails in many institutions both 80 business and public.

The prime objects of my present invention are to effect a saving in wiring which will render practicable the connection of 100 or more intercommunication telephones in 85 one system, and to develop a plan of supervision by monitor stations to more correctly meet the departmental conditions in the large institutions requiring so many telephones.

Another object of equal importance is to secure absolute secrecy of communication.

A further object, no less in importance than any, is the complete abandonment of all bell-hanger methods and the substitution 95 of strictly telephonic methods throughout, so the system may be connected to the public telephone system without detrimental effect.

I accomplish these objects by dividing the telephones into separate local groups, each 100 of which constitutes a complete intercommunication system, and connecting the separate groups for inter-departmental communication by means of suitable trunks. The telephones of one group may be conveniently located at various points in a single department, and a certain telephone 105 may be designated a monitor station where

all audible trunk signals are located and where all incoming trunk calls are received. The monitor station would appropriately be located in the office of the departmental head where an office boy or clerk would answer all incoming trunk calls, referring to and calling the proper local station when necessary. Trunk lines connecting with the public central exchange may be connected to each monitor station, or as many of them as desired, and extended to as many local stations in each group as occasion may require. In any case the telephone traffic of each department would come under competent supervision, and at the same time all communications would be absolutely secret.

Without regard to the exact scope and novelty, which will be pointed out in the claims, my invention generally consists, first, of a sealed secret service or private line system of telephonic intercommunication from one station to another of three or more stations, without the necessity of a central office, and without the serious objection of a third party being able, through any manipulation of his own telephone or switching devices or even by tapping any wires, except by opening up sealed parts, to listen in while two other parties are in communication; and secondly, of a secret trunk line connecting a group of stations in said system to another group in the same system, and also sealed at every point where the said trunk could otherwise be tapped for listening in, said trunk line being arranged so that, in each of said groups, only one station at a time can be connected therewith, unless the party at the said one station desires by means of his own switching apparatus to connect other stations, and provided at each station with means to indicate when in use at some other station.

Generally the organization comprising my invention consists of the combination of telephone, signaling and switching apparatus located at each of three or more stations, independent wires respectively connecting the apparatus at each one of the stations forming a group with the apparatus at each one of the remaining stations in said group, a trunk line connecting all the stations of one group to all the stations of another group, a common battery located at some convenient point for supplying signaling and talking currents, and common wires connecting the common battery with the apparatus at all of the stations.

By reference to the drawings, which form a part of this specification, a more detailed description will be given, and afterward the operation will be explained.

In the drawings: Figure 1 is a diagrammatic view showing the nature and principles of the system of the various local and trunk lines used in an embodiment of my invention;

Fig. 2 is a diagram of circuits for a pair of stations connected by a trunk line; Figs. 3 and 4 are face views respectively of the telephone sets of a monitor station, and an ordinary local station. Fig. 5 is a diagrammatic view showing the actual circuit conditions during trunk line telephonic communication; the circuit conditions during local communication may be traced in this figure by the dotted lines.

I will first generally consider the broad features and general aspects of the invention, and afterward describe in detail all the particular connections and circuits of a practical embodiment thereof.

Referring to Fig. 1, there is shown diagrammatically a complete system of twenty-five stations, each represented by a circle. The lines connecting the different stations represent ordinary telephone connections or wires, each line representing a pair of metallic wires of the usual form used in telephone work. In practice these wires are, of course, collected into compact cables and sometimes inclosed in metallic tubing extending from one station to another, but in the diagram they are drawn in a conventional way so as to more clearly illustrate the theory of the arrangement. It will be observed that the twenty-five stations are divided into five groups, and each group may be considered some local department of a factory. For instance, the different groups may correspond to five different buildings of a manufacturing establishment, and each building has five telephones at the different departments or rooms thereof. The different telephones or stations of the groups are designated by the numerals 1, 2, 3, 4 and 5, and the different groups are designated by the characters A, B, C, D and E. Some of the calls of this system will be local between the different stations of the same department, while part of the traffic will be inter-departmental, *i.e.*, from stations of one group to stations of other groups. In the first instance the system is purely an intercommunicating one, and operates in the same way as set forth in my prior application, No. 292,916. In the second case, the system is intercommunicating in the sense that it operates without any central exchange, but is a trunk system in the sense that it makes use of certain trunk wires or connections, which are common to a number of stations for connecting separate systems or groups of stations. The arrangement by which the intercommunicating groups of stations may be connected over trunk lines without the use of any central exchange, I consider an important feature of the invention. I also consider an important feature of the invention the arrangement by which busy signals are given when trunk messages are being sent. I also consider a very important feature of

the invention the arrangement by which trunk messages are absolutely secret, notwithstanding the fact that the trunk lines are common to all the stations of their groups. The general arrangement of the circuits by which the first and third of these features are secured will be clear from the diagram of Fig. 1. The details of the above and the particular arrangement of the circuits by which the busy signals are given in case of trunk messages will later appear from a consideration of the other figures of the drawings.

It will be observed that there are extending from the stations 1 of each of the groups A, B, C, D and E, four lines or pairs of wires, and these wires lead to each of the other four groups of the system in every case. For clearness the connections are shown in direct single lines, but it is to be understood that in practice pairs of wires will be collected into cable in metallic pipes or conduits. These lines or pairs of wires are the trunk lines or connections. They are extended through all of the stations 1, 2, 3, 4 and 5, of each of the groups, as shown. The last station at which they terminate in each group is what I call the monitor station, because at this station is located the monitor or person who looks after incoming trunk calls from distant stations. In addition to the four trunk lines passing through stations 1, 2, 3, 4 and 5, there are other lines or pairs of wires which interconnect between the different stations of each separate group. There are four of these lines or pairs of wires extending from each station to the other four stations of the group, and these would also be collected into cables and inclosed in metallic pipes in practice. These wires may be termed local lines as distinguished from the trunk lines. There are, therefore, eight different telephone lines or pairs of wires terminating in each station of the entire system, and by means of these eight telephone lines or pairs of wires, it is possible to reach any one of the other twenty-four stations of the system and establish an absolutely secret communication therewith. From this it is clear that a great saving of wiring is effected. The particular means by which this is accomplished will be later more fully described, but in order to enable the broad principles to be understood, I will consider the action in making different kinds of calls, both local and trunk. It is to be understood that certain signals *d* are located at each monitor station 5, in which the trunk lines or wires respectively terminate.

Supposing that station 5 of group E desires to communicate with station 2 of the same group: It is merely necessary for station 5 to so manipulate keys or switches or plugs as to apply a telephone set at the ter-

minal 2 thereof. If station 2 now applies its telephone set to its terminal 5, it is evident that stations 2 and 5 are telephonic communication over an absolutely private wire and without the use of any central exchange. In an exactly similar way, station 5 would communicate with station 1 or 3 or 4. Also stations 1, 3 and 4 would in like manner communicate with any desired station of the group. Thus all conditions of local intercommunication for any group are taken care of.

I will now assume that a station of group E, for example, station 5 desired to communicate with a station of group A, for example, station 1. The procedure is as follows: Station 5 of group E by certain keys and appliances hereinafter described applies a telephone set and also a battery current at the terminal A thereof. The effect of applying battery current to this trunk line or pair of wires is to produce both a visual and an audible signal at the monitor station No. 5 of group A. The monitor thereupon connects a telephone set to this particular trunk line and inquires what is wanted. The person at station 5 of group E, who has his telephone set connected, answers that he wishes to talk to station 1 of group A, and the monitor at station 5 of group A then calls up station 1 over the local system. As soon as station 1 of group A has its telephone set connected to the trunk line, the desired communication is established. Not only is this communication established, but it is absolutely secret, because, on account of certain appliances hereinafter described, the connection of the telephone set of any station cuts off the line to stations beyond during the communication. Thus stations 2, 3, 4 and 5 of group A would be cut off when station 1 was talking. Stations 1, 2, 3 and 4, of group E, are likewise excluded from cutting into the conversation, because any attempt to cut in would immediately cut out the stations beyond, thereby interrupting the conversation. Thus only two stations can be in a talking circuit on any trunk at a given time. As has been already mentioned, the battery current is applied to the trunk lines during the time that they are busy, and these battery currents exhibit busy signals at all the stations to prevent interruption by mistake. Thus the three important features of the invention are secured, namely, the various groups of stations connected by intercommunicating trunks; secondly, the absolute secrecy of the conversation, not only between stations of the same group, but in trunk messages as well; and, finally, the production of busy signals when the trunk lines are being used. There is also secured the monitor supervision mentioned in the first part of this specification, since only the monitor stations of the various groups are

provided with signals *d* for the incoming trunk messages. Accordingly the monitor of each local group or department passes on the propriety of the incoming message before the communication is established, and in case it is not official or proper, the monitor is able to take the appropriate action. If the communication is a proper one, he merely notifies the appropriate station of his group which then goes in on the line and the communication thereafter is absolutely secret even from the monitor. Ordinarily, however, the monitor could give all necessary information without referring to other stations, since the monitor station is located in the office of the departmental head.

I will now describe more in detail the practical embodiment of my invention herein disclosed. To facilitate a comprehensive understanding, I will first briefly point out the principal features of a trunk line joining two local groups naming the advantages of each feature. In the first place the same pair of wires is used for both signaling and talking. Where this can be done the economy in cabling is obvious. To this end, therefore, each end of every trunk normally terminates in a signal device, so either monitor station in each of which one of the signal devices is located, is available to be signaled at all times when the trunk is idle. These signal devices are adapted to be operated by the steady battery currents which are supplied from a central source to each station throughout the system by a common pair of feed wires. This same battery is used for all signaling and talking, the advantage being, of course, the saving in cost of equipping for more than one current source. Each signal device when operated displays a visual signal which indicates the trunk over which the call comes. The operation of the visual signal also actuates the closing of a circuit to give an audible signal which is adapted to operate with any individual visual signal. This is in effect an annunciator, and the audible signal is the ordinary battery bell or buzzer which is located at each station for calling the party to the telephone. To call the distant monitor station battery is simply applied to the line at any one of the local stations. In applying this battery current, however, it is essential that the connections are properly polarized for reasons which will later appear. The battery is applied to the line simply by bridging the primary of the telephone set across the trunk, and lifting the telephone receiver from the hook to supply the transmitter and primary coil with current in the usual manner. Whether the monitor station or one of the other local telephones is connected as above to the trunk, the extension of the trunk to the signal device of the local monitor is cut off,

so only the distant monitor is called. From the moment the battery is applied to the line by a telephone of a local group to signal the monitor station of a distant group, all intermediate stations in both groups are notified by visual signals, one of which is located in each telephone, that the trunk is busy. To keep these busy signals actuated the battery current remains on the line during the conversation.

Further details will now be explained by reference to Fig. 2. In this figure is shown diagrammatically and typically a full detail arrangement of the circuits and parts of two different stations, for example, station 1 of group A and station 5 of group E, with the trunk line or pair of wires EA—A'E' connecting between the two sections. Station 1, group A, is the first station which the trunk line AE—A'E' enters in this group. Passing into station 1, over the binding posts marked E on terminal strip *t'l*, the trunk wires AE and A'E', in normally closed circuit through the trunk key E^k, pass out over binding posts marked 2 on terminal strip *t'l*, and then to station 2 (not shown) of the same group A; and so on the method of connecting and passing the trunk wires through stations 2, 3 and 4 would be exactly the same as in station 1, 95 and the apparatus and circuits at stations 2, 3 and 4 would be like station 1. The last station, however, to which the trunk is connected in each group is always the monitor station, and this station has a different 100 assemblage of trunk apparatus and the trunk wiring is different from that of the other stations in the same group. But all the monitor stations are alike, and station 5, group A, would be like station 5, group 105 E, which is shown complete in Fig. 2. The trunk wires AE and A'E' enter station 5, group E, over the binding posts marked A, and terminate in the springs *x* and *x'* respectively of the trunk key A^k. It is understood that the trunk is looped in and out of each of the stations 1, 2, 3 and 4, which are omitted from the drawing as indicated by the dotted lines in the trunk wires AE and A'E'. At the monitor station each 115 trunk line terminates in a trunk key which in normal position connects the trunk with a drop signal. The trunk AE, A'E' normally ends in the drop A^d. The drops B^d, C^d and D^d are the signals for the trunks 120 connecting with groups B, C and D respectively. Each one of these drop signals has its night bell contacts connected to ring the signal bell E when the drop shutter falls.

The visual signal E^v at station 1, group 125 A, is bridged across the trunk wires AE and A'E', to indicate when the trunk is busy at some other station in the same group. The visuals B^v, C^v and D^v are for the trunks connecting with groups B, C and D respec- 130

tively. From station 5 in group E there are, of course, also the independent direct lines to the other four stations in this group. The lines to stations 1, 2, 3 and 4 would 5 terminate at pairs of binding posts marked 1, 2, 3 and 4 respectively on terminal strip t^6 . The pair of binding posts marked O are used for the battery feed wires. Springs x and x' of keys k^1 , k^2 , k^3 , and k^4 are connected to binding posts marked 1, 2, 3 and 4 respectively, and therefore constitute the permanent terminals of the local line wires. These keys are used to switch the local lines 10 from the signaling circuit to the talking circuit of the station. The grouping key g is used to determine the calling station when the signal comes from one of the stations in the same group.

The telephone set at each station consists 20 of the transmitter T, receiver R, induction coil I, retardation coils r and r' . The hook switch h also plays a part in switching battery on and off the telephone set according to whether the receiver is off or on the hook. 25 The condensers c and c' put the secondary circuit of the telephone in closed inductive relation with the primary without subjecting the receiver to the passage of direct battery current through it, and at the same time 30 keep the battery currents from passing to local lines and interfering with the local line signaling. The transmitter T and primary p of the induction coil I are in series and connected permanently through the retardation coil r to the negative battery feed, and 35 through the retardation coil r' to the hook switch h by means of the wire n , and hook switch h , which is open when the receiver R is on the hook, is in turn connected to the 40 positive battery feed. The receiver R and secondary s of the induction coil I are in series and connected to the wires u and u' . The wires u and u' are connected to wires u'' and u''' respectively through the condensers c and c' , the wires u'' and u''' being 45 connected to the negative and positive battery feeders through the retardation coils r and r' respectively. The telephone set therefore has its primary and secondary 50 circuits connected in multiple through the condensers c and c' . An important feature in this construction and one to which particular attention is called is the fact that the adjacent terminals of the primary and secondary windings are joined together through 55 the condensers, and, of course, the transmitter and receiver, i. e. the terminal of the secondary winding adjacent to the negative battery terminal of the primary winding, is 60 connected by wire u , condenser c and wire u'' to the terminal of the primary coil having negative battery, and the terminal of the secondary adjacent to the positive terminal of the primary is connected through 65 the receiver R, by wire u' , condenser c' ,

wire u''' , and through the transmitter T, to the terminal of the primary coil having positive battery. The reason for this will later appear.

For the purpose of sending signals to 70 other stations in the same group a push button b is located at each station, and for receiving signals an electric bell E is included in the equipment at each station. One side of the electric bell E is permanently connected to the negative battery feed, and the other side is connected to the common line e' . The complete circuits of the independent direct lines between the five stations in the same group, and also the operation of 75 them has already been fully explained in my application, Serial Number 292,916, filed December 22, 1905, and, therefore, only the details of the trunks need be explained 80 herein.

At station 1, group A, the trunk wires AE and A'E' connect through binding posts E on terminal strip $t'l$, to the movable springs x and x' of trunk key E^k , and the spring blades of the other trunk keys are correspondingly connected to the other trunk line wires. This key operates to disconnect the rest of the stations of group A from the trunk wires AE and A'E', and to connect these trunk wires to the telephone set at station 1, 90 from which the trunk connection is continued to station 2 of group A. The coil terminals of the visual signal E ^{v} , at station 1, group A, are connected to the springs i and i' of key E^k . This visual is, therefore, bridged across the extension of the trunk line 95 leading to station 2 of group A. At stations 2, 3 and 4 of group A and stations 1, 2, 3, and 4 of group E, the trunk line would be wired as above shown for station 1 of group A, the visual signal being always connected 100 to the extension of the trunk leading to the next station. At station 5, of group A, the trunk line would be terminated in a drop signal and wired as shown at station 5, group E.

115 I have said that in applying battery to the line to call a distant monitor, it is essential that the connections are properly polarized. This will be clear from an inspection of the drawing. The bell E has one terminal permanently connected to negative battery. The other terminal must therefore get connection with positive battery to ring the bell. The wire e' connected to the latter terminal, and which also connects at monitor stations 120 with the night bell contacts w , must, therefore, receive a positive current. To this end the shutters of the drops d , which engage contacts w , are connected in each instance 125 to receive a positive current. For example, 130

- the shutter f of the drop A^d at station 5, group E, is connected to the contact i , normally in contact with the spring blade x of the trunk A^k . The spring blade x in 5 any trunk key is adapted to be brought into contact with contact point o of the same key, and the latter contact point is in every case connected to the positive battery tap of the retardation coil r' at the same station.
- 10 It is, therefore, essential that the line spring x in every trunk key connects with the corresponding spring x in every other key of the trunk at other stations. Thus it will be seen that if a positive battery current is sent 15 over the trunk wire AE , by bringing the blade x of the trunk key E^k at station 1, group A, into contact with the contact point o of the same key, when the receiver R is off the hook h , the positive current will enter 20 station 5, group E, over the blade x of the trunk key A^k . Therefore when the night bell contacts are closed in the drop A^d , the positive battery current will be conveyed to the bell E over the wire e' .
- 25 The method already explained for connecting all of the stations of group A with all of the stations of group E is the one employed to connect all the stations of any group with all the stations of any other group in the system. The means by which 30 the stations along the extension of a trunk line, which extension has been interrupted at a preceding station on the line, may determine whether the trunk line is in use, will 35 later appear from the description of the operation.
- An occasional condenser c'' may be bridged across the battery feed at any point in the system to absorb stray telephonic currents. 40
- In my present arrangement of the local apparatus for the stations, I have adopted a slightly modified construction of the push button b for signaling on the local lines. 45 This push button is adapted to open the wire u to the secondary of the induction coil when the battery is applied to this side of the circuit for signaling. The reason for doing this is that when the secondary circuit of the 50 telephone is connected to a very long line, a considerable condenser effect may be built up through the secondary s , wire u' , and the open side of the line, if the connection of the wire u to the secondary s is not interrupted.
- 55 The static charge thus given would be communicated to parallel lines by induction and might be sufficient to interfere with the proper working of a very extensive system. The opening of the circuit to the other side 60 of the line at the push button b , when the signal battery is applied to one side of the line, thus destroying the open branch, eliminates all chances of static kicks. With this slight modification of the circuit at the push button b and the changes shown in the pri-

mary and secondary circuits of the telephone set, the apparatus and circuits for the operation of the local lines is identically the same as disclosed in my former application, No. 292,916. The operation is exactly the same. 70

Fig. 3 shows a sealed cabinet or containing case for inclosing all parts of the apparatus and circuits located at the monitor station of any of the five groups. Mounted on the outside of the cabinet are only the transmitter, the bell, the buttons for the push button and keys, and the shutters of the trunk drops. All other parts are within the sealed cabinet. 75

The cabinet shown in Fig. 5 is for inclosing all the apparatus at stations which are not monitor stations, the only difference being that in place of the drop shutters the gridiron fronts of the trunk busy signals are shown. 80

Fig. 6 shows diagrammatically the actual talking circuits between two stations in this system. It is to be understood that the keys, etc., have been omitted, and the circuits otherwise stripped of details. The telephone set here shown has already been explained with reference to Fig. 2. The telephone sets of both stations are shown connected through retardation coils to common wires from the battery B, which is, of course, the 90 common battery of the system. For conversation between two stations in the same group the line circuit is represented by the dotted lines, while the circuit for trunk line communication is represented by full lines. 95 This diagram will be found convenient in considering the action of the telephonic currents which will later be explained. 100

The construction having been sufficiently described, the operation will now be explained. 105

Let it be assumed that a party at station 1 of group A desires to call and talk with the monitor at station 5 of group E. The party at station 1, group A, will determine 110 from the visual signal E^v whether the trunk to group E is busy. If the trunk is not in use at some other station, the party at station 1 will operate the trunk key E^k and lift his receiver from the hook and place it 115 to his ear. In removing the receiver R the hook switch h closes battery through the primary circuit of the telephone, and by operating the key E^k the primary circuit of the telephone is connected with trunk line 120 wires AE and $A'E'$. Thus a part of the battery which is being supplied to the primary circuit of the telephone is shunted out over the line wires AE and $A'E'$ which have 125 signals bridged across them at other stations. In operating the key E^k , the line spring blades x and x' are moved out of contact with the contacts i and i' , thus opening the extension of the trunk to the visual 130 E^v and to the other stations in the same 135

group A, and the springs α and α' are moved into contact with contacts o and o' respectively, thus connecting the trunk wires AE and A'E' with the primary of the telephone and also with positive and negative battery through wires u''' and u'' and retardation coils r' and r respectively. Thus the telephone is connected and battery is applied to the trunk wires AE and A'E' 5 at station 1 of group A. At stations 1, 2, 3 and 4 of group E, the visual busy signals there bridged across the line will be operated and held from the moment the battery is applied at station 1, group A. At 10 15 the monitor station 5 of group E the drop signal A^a, in which the trunk wires AE and A'E' normally terminate in this station, will be operated by the battery applied at station 1 of group A. The shutter f in falling will close the positive side of the trunk to the battery bell E in the manner already made clear from the detailed description of the construction. The bell E will be rung, and will continue to ring 20 25 as long as battery is being supplied from the distant calling station, or until the monitor answers. The shutter f will remain down until restored by the monitor. Thus, if no one is on hand to answer the call, the bell E will cease to ring when the calling party clears out and removes battery at the other end, but the drop shutter remaining down will always indicate the department which has called. Assuming the monitor is 30 35 on hand to answer the call, he does this by connecting his telephone in exactly similar manner and operating the trunk key in same way as did the party at station 1 of group A. In operating the trunk key A^k, the spring blades α and α' break contact with inside contacts i and i' and make contact with outside contacts o and o' respectively. Thus the drop A^a is cut off from the trunk and the flow of battery being interrupted the bell E ceases to ring. The 40 45 monitor may now restore the shutter f . Battery current is now being supplied to the trunk at the monitor station in the same manner as at the distant station, thus augmenting the current for holding the visual busy signals at the intermediate stations. It is to be understood that the impedance of the coils in the busy signals is so high as not to interfere with the flow of the telephone currents, and the parties at the two 50 55 stations now proceed to talk. Should the calling party desire to talk with some one at another station, say station 2 of group E, he would make the fact known to the monitor, whereupon, it being a proper call and the connection permissible, the monitor would call station 2 over the local system and tell the party there to go in on the trunk to group A. In so doing the party 60 65 at station 2 would cut off stations 3, 4, and also the monitor station 5 of group E in exactly the same manner as station 1 of group A cut off the extension of the trunk to the other stations of the same group. Thus the conversation is always absolutely 70 secret between the two parties in communication, as the intermediate stations cannot cut in without interrupting the talk and the stations along the extension which is cut off cannot cut in at all. The manner in 75 which the monitor calls the local station 2 in group E need not be explained, as the operation is the same as in my former application of record. It is sufficient to assume in this instance that the monitor is 80 able to transact the business with the calling party without referring to any other station. When they have finished talking, each party hangs up his receiver. At each station the receiver hook-switch h automatically removes battery from the trunk as well as from the telephone set by opening the positive side of the battery. A trip mechanism attached to the receiver hook (not shown because well known) also automatically restores the trunk key to the normal position. Thus at station 1 of group A the trunk circuit is made continuous on to the monitor station of the same group, and at the monitor station 5 of group E 90 95 the drop A^a is again bridged across the trunk and either monitor station is again available to be called from any station of the distant group.

From the foregoing it has been made clear 100 how the intermediate stations between two connected stations are notified by visual signals that the trunk is busy. It may not have been apparent, however, that the stations along an extension of the trunk which is cut off also have means of determining when the trunk is in use at some other station. The stations of the interrupted extension have no visual means of knowing, but they may determine whether the line is busy by 110 connecting to the trunk and listening thereon. The primary and secondary of the telephone set being closed in parallel with themselves, and besides the busy signals at other cut off stations, would give closed circuit conditions to the line and the usual side tone would be heard in the receiver by speaking into the transmitter, so this would give no indication. But if the trunk is cut off at some other station the line will be 120 quiet, whereas, if the line is continuous to the distant monitor the action of the vibrating bell, in first closing and then interrupting the connection of the positive side of the line through the bell, will set up electrical oscillations in the line which will manifest themselves in the receiver of the calling party. If he does not hear the characteristic buzz, he knows the line is busy. This effect may be made as marked as need 130

be by increasing the resistance of the drop over that of the vibrating bell, which is, of course, ordinarily very low. Thus it will be seen that every station has a practical means of determining when a trunk line is busy at some other station even when the trunk is interrupted at a preceding station.

The ordinary operation having been explained, other conveniences of the system will readily occur to the minds of those versed in the art. Without describing further details in the manipulations of the apparatus and switching of the circuits, I will now consider the action of the telephonic currents in both local and trunk connections. Attention has already been called to the novel construction of the circuits of the telephone instrument. It now remains to point out the advantages of this new arrangement.

It has been noted that the primary and secondary circuits of the telephone are connected in parallel to the line. This is true whether the line in question is a trunk or a local line, but the connection between the primary and secondary is merely inductive, and the connection of trunk lines is made to the primary while the connection of local lines is made to the secondary. This is clearly illustrated in the diagram, Fig. 5. It will be seen that the condensers c and c' separate the primary and secondary circuits of the instrument, and that the connection of the trunk line is made on one side of the condensers, while the connection of the local line is made on the other side of the condensers. The condensers serve, therefore, to keep steady battery currents out of the receiver, thus making it unnecessary to polarize the receiver, and also prevent battery current from flowing to the local lines and interfering with the local line signaling. At the same time the condensers permit the telephonic connection of the receiver or secondary circuit to trunk lines, which may have steady battery current from the city exchange passing through them while in use for the operation of signals as already described. Thus it will be seen that the arrangement of the telephone circuits and their connection to the lines is such as to permit of the proper electrical conditions on each class of lines and to give the proper telephonic conditions also.

In addition to permitting proper electrical and giving proper telephonic conditions to the lines, the construction of the circuits of the telephone instrument is such that the combined action of the primary and secondary circuits betters the telephonic transmission. To get the mutually augmentative effect between the primary and secondary, however, it is essential that the connections of the terminals of each be according to the fixed rule pointed out earlier in this specifi-

cation and clearly illustrated in the diagram, Fig. 5. This diagram will be referred to in considering the combined action of the primary and secondary.

Assume the transmitter T is at rest. It has a certain normal resistance. Steady current will flow from the positive battery terminal through the transmitter T and primary p to the negative battery terminal. The direction of this flow will be as indicated by the arrow adjacent to the primary p . The condensers c and c' , being in series with each other (through the receiver and secondary) and bridged across the battery feed, will be charged to the same potential that exists on the battery feed. The polarity of the charge in the condensers is indicated by positive and negative signs. If the transmitter T now be spoken into, the instantaneous effect of the voice pressure upon the diaphragm will be to lower the resistance of the transmitter and increase the flow of current through the transmitter and primary in the direction of the arrow. The increased flow of current in the primary will cause a current to be induced in the secondary s in the direction of the arrow adjacent to the latter, and the lowering of the potential across the terminals of the primary will cause the condensers c and c' to be discharged. The discharge from the condenser c' will pass from the positive plate through the transmitter T and primary p , in the direction of the adjacent arrow, and by wire u'' to the negative plate of the condenser c . This discharge being in the same direction as the primary battery current will augment it. The discharge from the condenser c will pass from the positive plate through the secondary s , in the direction of the adjacent arrow, and the receiver R to the negative plate of the condenser c' . This discharge being in the same direction as the induced current in the secondary will augment it. Upon the return of the transmitter diaphragm to the normal position, the resistance will be raised to normal, the current flow in the transmitter and primary will ebb and the potential between the terminals of the primary will be raised again. The ebbing of the current flow in the primary will cause a current to be induced in the secondary s in the direction opposed to the arrow adjacent to the latter, and the rise in potential between the terminals of the primary will cause the condensers c and c' to be charged again to the same potential. The flow of current to the positive plate of the condenser c' , whether drawn from the line or from the positive battery terminal, will tend to still further diminish the flow of current through the transmitter and primary. The current flowing to the positive plate of the condenser c will pass through the receiver R and secondary s in the direction opposed to

the arrow, and will therefore coincide with the induced current caused by the ebbing of current in the primary. Thus it will be seen that the current changes impressed upon the line will be of much greater range than they would be if no induction coil were used, having separate primary and secondary circuits connected as shown. It will, of course, be understood that the retardation coils r and r' at each station are to keep the quick variations in the resistance of the telephone circuit from effecting the steady flow of battery current to the line. This tends to keep the full range of the current changes on the line, thus producing the maximum effect on the receiver of the receiving station. Thus the action of the primary and secondary circuits, when connected as shown, betters the transmission, and the combined action is mutually augmentative. But if the connections between the primary and secondary are reversed, the converse will be true. I have verified this in my experiments by reversing the connection of the secondary to the condensers, connecting the wire u to the condenser c' and the wire u' to the condenser c , and a falling off in both volume and clearness approximating 50 per cent. resulted.

The action and efficiency of the telephone set is about the same on both local and trunk lines. In the tests made on a given line, no difference could be detected in the transmission whether the line was connected to the primary or secondary circuits of the two telephone sets, nor did it make any difference in the transmission when the primary of one set and the secondary of the other set were connected to the line. Furthermore, the action of the telephonic currents was the same with one side of the line connected to the primary and the other side connected to the secondary. The experiments thus proved that the telephonic action is the same on the line when connected to any point in the bridge between the primary and secondary and on either side of the condensers. Reversal of the line wires of course, made no difference, but reversing the connection between the primary and secondary cut down the transmission in each line test above described.

Referring now briefly to the flexibility of and general utility of my system, it may be seen from the foregoing specification that the economy of line wiring, or cabling, is so great as to render practical the connection of 100 or more intercommunication stations in one system. The reduction of the number of lines also reduces the number of line switching devices at each station, thus making practical the use of a small telephone cabinet or containing case for inclosing all of the switching apparatus and parts which are necessary for connection with 100 or

more stations. For example, in a system of 100 stations divided into 10 groups of 10 stations each, only nine local and nine trunk keys would be required at each telephone, these 18 keys together with the local signaling and local grouping keys at each station making in all only 20 buttons for each telephone in a system of 100 stations. For any number of stations found in practice the monitor supervision will be found effective, and all conversation, may be kept absolutely secret.

The system may without detrimental effect be connected with any public exchange system, by adding exchange trunk line equipment as required, and the telephone set herein disclosed will be found highly efficient for long-distance talking. In fact each intercommunication telephone is also a good long-distance telephone.

What I claim, is:—

1. In a telephone system, a plurality of groups of stations every group of which is connected to every other group by separate line wires constituting trunk connections, and a plurality of stations in each group every station of which is connected to every other station by separate local line wires, said trunk line wires being extended through all of the stations of their respective groups, and means whereby both battery and voice currents are impressed upon the trunk lines during telephonic communication.

2. In a telephone system, a plurality of groups of stations every group of which is connected to every other group by separate line wires constituting trunk connections, and a plurality of stations in each group every station of which is connected to every other station by separate local line wires, said trunk line wires being extended through all of the stations of their respective groups and terminating in a station having signals different from the other stations and constituting a monitor's station for each group, 100 and means for impressing a battery current on said trunk line wires when they are transmitting messages, to operate the said signals.

3. In a telephone system, a plurality of groups of stations every group of which is connected to every other group by separate line wires constituting trunk connections, and a plurality of stations in each group every station of which is connected to every other station by separate local line wires, said trunk line wires being extended through all of the stations of their respective groups, busy signals connected to said trunk line wires, and means for impressing a battery current on said trunk line wires when they are transmitting messages, to operate the said signals.

4. In a telephone system, a plurality of groups of stations each group of which is connected to every other group by separate

- line wires constituting trunk connections and a plurality of stations in each group every station of which is connected to every other station by separate local line wires, 5 said trunk line wires being extended through all the stations of the respective groups, and means for interrupting said trunk line wires beyond any station of a group when such station is in telephonic communication over 10 said trunk line wires.
5. In a telephone system, a plurality of groups of stations each group of which is connected to every other group by separate line wires constituting trunk connections 15 and a plurality of stations in each group every station of which is connected to every other station by separate local line wires, said trunk line wires being extended through all the stations of the respective groups, 20 means whereby induced currents alone are impressed on the local line wires during telephonic communication, and means whereby both battery current and voice currents are impressed on the trunk lines during tele- 25 phonic communication.
6. In a telephone system, a plurality of groups of stations each group of which is connected to every other group by separate line wires constituting trunk connections 30 and a plurality of stations in each group every station of which is connected to every other station by separate local line wires, said trunk line wires being extended through all the stations of the respective groups, busy 35 signals bridged across said trunk line wires at each station, and means whereby a busy indication is given at said signals when said trunk lines are connected for telephonic communication.
- 40 7. In a telephone system, a plurality of groups of stations each group of which is connected to every other group by separate line wires constituting trunk connections and a plurality of stations in each group 45 every station of which is connected to every other station by separate local line wires, said trunk line wires being extended through all the stations of the respective groups, busy 50 signals, and means whereby a busy indication is given at said signals when said trunk lines are connected for telephonic communication.
8. In a telephone system, a plurality of groups of stations each group of which is connected to every other group by separate line wires, a plurality of keys at each station by which any desired set of line wires may be exclusively connected to a telephone set, and an additional key at each station by 55 which said telephone set may be connected to a plurality of line wires simultaneously.
9. In a telephone system, a plurality of groups of stations each group of which is connected to every other group by separate 60 trunk line wires, and a plurality of stations 65

in each group every station of which is connected to every other station by separate line wires, a telephone set at each station having a transmitter circuit, means whereby the battery current of said circuit can be directly applied to the trunk lines, and means whereby battery current in said trunk line is interrupted in case of local communication. 70

10. In a telephone system, a plurality of groups of stations each group of which is connected to every other group by separate line wires constituting trunk connections and a plurality of stations in each group every station of which is connected to every other station by separate local line wires, a source of potential difference, a transmitter connected across the terminals thereof, and having the usual induction coil, and means whereby the fluctuating potential 80 across said transmitter and the primary of said induction coil is impressed directly on said trunk lines during telephonic communication, and means whereby the induced voice currents in the secondary of said induction 85 coil are inductively impressed on said trunk lines during telephonic communication. 90

11. In a telephone system, a plurality of groups of stations each group of which is connected to every other group by separate line wires constituting trunk connections and a plurality of stations in each group every station of which is connected to every other station by separate local line wires, a telephone set including a transmitter, receiver and an induction coil, means whereby the potential across said transmitter and the primary of said coil is directly impressed on said trunk lines during telephonic communication, and means whereby the fluctuating potential of the secondary of said coil is inductively impressed on said trunk lines during 95 telephonic communication. 100

12. In a telephone system, a plurality of groups of stations each group of which is connected to every other group by separate line wires constituting trunk connections and a plurality of stations in each group every station of which is connected to every other station by separate local line wires, a telephone set including a transmitter, a receiver, and an induction coil, means whereby the battery current through said transmitter and the primary of said coil is directly impressed on the trunk lines during 110 telephonic communication thereover, and means whereby said current is cut off from the local lines. 115

13. In a telephone system, a plurality of local lines, a plurality of groups of stations each group of which is connected to every other group by separate line wires constituting trunk connections, means whereby a battery current is permanently impressed on the trunk lines during telephonic communication. 120 125 130

cation, and means whereby battery current may be temporarily impressed on the local lines during telephonic connection for signal purposes.

5. 14. In a telephone system, a line having a plurality of stations, each of said stations having a telephone set and means for connecting said set to the line and cutting off succeeding stations of the line, means for 10 applying battery current and telephone sets to the line at the succeeding stations, and a call bell at a distant station of the line, whereby the circuit connections of said bell produce a buzz at a subscriber's station 15 when no intermediate station is in the circuit, but no buzz when an intermediate station is in the circuit.

15. In a telephone system, a line having a plurality of stations thereon each of said stations having a telephone set and means for connecting said set to the line and cutting off succeeding stations of the line, means for applying battery current and telephone sets to the line at the succeeding stations, 20 and means for producing a buzz at the telephone set of such succeeding stations when any intermediate station is not in connection with the line.

16. In a telephone system, a plurality of 30 groups of stations each group of which is connected to every other group by separate line wires constituting trunk lines, a plurality of stations in each group every station of which is connected to every other station 35 by separate line wires, a common trunk line including all the stations of any group said

trunk terminating in a monitor station, and means for establishing signals at the monitor's station to the exclusion of all other stations whereby all trunk communication is 40 supervised at the monitor's station.

17. In a telephone system, a plurality of groups of stations each group of which is connected to every other group by separate line wires constituting trunk lines, a plurality 45 of stations in each group every station of which is connected to every other station by separate line wires, a trunk line common to every station of any group and terminating in a monitor's station, and 50 means at such monitor station by which the trunk communication is supervised theret.

18. In a telephone system, a plurality of groups of stations each group of which is connected to every other group by separate 55 line wires constituting trunk lines, a plurality of stations in each group every station of which is connected to every other station by separate line wires, a trunk line common to every station of any group and terminating in a monitor's station, and 60 means at the monitor's station for supervising the trunk communication but not the local communication between stations of the 65 same group.

In witness whereof, I subscribe my signature, in the presence of two witnesses.

RICHARD M. BEARD.
